United States Patent Office

Des. 212,741

Patented Nov. 19, 1968

212,741

DINER

Vincent F. Giannotti, 6 Duval Court, Fairfield, N.J.
07470; Ralph Manno, 432 Ridge Road, Cedar Grove,
N.J. 07009; and Giro R. Manno, 12 Manor Road,
Livingston, N.J. 07039

Filed Mar. 1, 1967, Ser. No. 6,006

Term of patent 14 years

(Cl. D13—1)

FIG. 2

FIG. 3

FIG. 1 is a perspective view of a diner showing our new design;

FIG. 2 is an end view thereof with the umbrella support being broken away in the center thereof for convenience of illustration only; and

FIG. 3 is a top plan view thereof.

The end of the diner opposite the end shown in FIG. 2 is plain and the other side of FIG. 1 is the same as in FIG. 1.

The dominant features of the design resides in the portions shown in full lines.

We claim:

The ornamental design for a diner, as shown and described.
